(57) **CLAIM**

The ornamental design for a television receiver, as shown and described.

DESCRIPTION

FIG. 1 is a perspective view of a first embodiment of a television receiver showing my new design;

FIG. 2 is a front elevational view thereof;

FIG. 3 is a left side elevational view thereof;

FIG. 4 is a right side elevational view thereof;

FIG. 5 is a top plan view thereof; and

FIG. 6 is a bottom plan view thereof.

FIG. 7 is a perspective view of a second embodiment of a television receiver showing my new design;

FIG. 8 is a front elevational view thereof;

FIG. 9 is a left side elevational view thereof;

FIG. 10 is a right side elevational view thereof;

FIG. 11 is a top plan view thereof; and

FIG. 12 is a bottom plan view thereof.

FIG. 13 is an enlarged perspective view thereof along the lines 13-13 and 13'-13' of FIG. 7;

FIG. 14 is another enlarged perspective view thereof along the lines 14-14 and 14'-14' of FIG. 7; and,

FIG. 15 is another enlarged perspective view thereof along the lines 15-15 and 15'-15' of FIG. 7.

FIG. 16 is an enlarged front elevational view thereof along the lines 16-16 and 16'-16' of FIG. 8;

FIG. 17 is another enlarged front elevational view thereof along the lines 17-17 and 17'-17' of FIG. 8; and,

FIG. 18 is another enlarged front elevational view thereof along the lines 18-18 and 18'-18' of FIG. 8.

Portions in broken lines are for illustrative purposes only and form no part of claimed design. Dot-dash broken lines define the boundaries of, but not included in, the claimed design.
